UNITED STATES PATENT OFFICE.

ROY C. BAKER, OF WOLLASTON, MASSACHUSETTS.

METHOD OF AND MEANS FOR MARKING BOOK SIGNATURES.

Application filed June 30, 1923. Serial No. 648,748.

To all whom it may concern:

Be it known that I, ROY C. BAKER, a citizen of the United States, and a resident of Wollaston, in the city of Quincy, county of Norfolk, and State of Massachusetts, have invented an Improvement in Methods of and Means for Marking Book Signatures, of which the following description, in connection with the accompanying drawings, is a specification, like characters on the drawings representing like parts.

This invention aims to improve methods of and means for marking book signatures to facilitate assembling them preparatory to binding them.

The invention will be best understood by reference to the following description, when taken in connection with the accompanying drawings of one specific embodiment thereof, while its scope will be more particularly pointed out in the appended claims.

In the drawings:

Fig. 1 is a front elevation of a signature marking machine exemplifying the invention;

Fig. 2 is a sectional view on line 2—2 of Fig. 1;

Fig. 3 is a detail plan on an enlarged scale, showing the marker and the actuating means therefor; and

Fig. 4 is a front elevation of the parts shown in Fig. 3, the marker and its carrier being partly broken away, the better to illustrate the actuating means.

Referring to the drawings, and to the embodiment of the invention which is illustrated therein, there is shown a marking machine having a signature support, or holder, comprising front and back shoulders 5 and 6, presenting a trough into which the folded signatures are placed with their backs or folded edges against the back wall 6, one of the signatures being indicated in dotted lines in Fig. 2, and designated 7. Herein, the front and back walls of the trough are inclined as shown in Fig. 2, thereby to utilize gravity to bring the corresponding edges of the signatures into the proper planes. The trough has end walls 8, and is mounted on appropriate supports 9 and 10, conveniently secured to the end walls, as by screws 11 and 12. In the present example, the supports present feet 13 and 14, which may be secured to a bench, or other convenient support, as by screws 15. The signatures to be marked are placed face to face in the trough, and

are held in fixed position by appropriate means, such as a movable wall 16, which is mounted to slide along the front and back walls 5 and 6, and is sufficiently weighted to hold the signatures in place against one of the end walls.

The marking of the signatures is accomplished by the use of a marker, such as an absorbent pad 17, conveniently in the form of a strip of felt, to which ink or other appropriate marking fluid may be applied, and which will hold a supply sufficient for a considerable period. This marker extends transversely of the book signatures, or in other words, it is transverse to the end walls 8. The marker is appropriately held in a holder 18, herein comprising a bar provided with a groove 19, in which the marker is received. (See Fig. 2.) The holder is secured, as by screws 20, to a carrier, herein comprising a bar 22. This bar presents a guide which guides the carrier, the holder and the marker in a path transverse to the signatures.

The marking of the signatures is accomplished by rubbing contact of the marker with all of the signatures simultaneously. In the present example, the marker is first brought into contact with the signature, and is then moved lengthwise to cause the rubbing contact. This is accomplished by the use of two cams 23, presented by the bar 21 and cooperating with cam followers, herein studs 24, which are secured to the bar 22 by nuts 25. These studs are headed as at 26 to hold the bar 21 in place on the bar 22. The cams present oblique portions 27 and horizontal portions 28. It follows that lengthwise movement of the bar 21 from the position shown in Figs. 3 and 4 toward the left is accomplished by movement of the marker 17 into engagement with the signatures, followed by lengthwise rubbing movement of the marker across the signatures. Herein, the carrier bar, upon being released, is restored to its initial position by a spring 29, which, as best shown in Fig. 3, has first one end secured as by a pin 30 to the movable bar 21, and has its other end secured as by a pin 31 to the fixed bar 22. The movable bar constituting the carrier may be provided with a handle 32, to be grasped by the operator for the manipulation of the marker.

The several signatures which are to compose the book should be marked at different

points, so that when the signatures are assembled, the marks shall serve as a guide, as by collectively presenting a diagonal line across the back of the collated signatures. 5 To this end, therefore, the marker and its actuating mechanism are adjustable lengthwise of the backs of the signatures. In the present embodiment of the invention, this is conveniently accomplished by attaching 10 the supporting bar 22 to a pair of racks 33, appropriately secured to the supporting bar as by screws 34 (see Fig. 3), said racks meshing with pinions 35 secured to a shaft 36, the latter being mounted in bearings 37, 15 which depend from rack guides 38 to the under side of the wall 6. (See Fig. 2.) To the shaft is secured a knurled handle 39, which may be grasped to rotate the pinion shaft, thereby to move the marker lengthwise of the signatures. 20

By reference to Figs. 1 and 2, it will be noted that the back wall 6 and the end walls 8 present an opening 39, whose dimensions are such as to permit the described adjustment of the marker and the movement thereof into contact with the backs of the signatures. 25

The marker may be secured in the selected 30 position of adjustment by any appropriate means, such as a pin 40, which may be inserted in any one of a series of perforations 41 in one of the rack bars (see Fig. 2), and the latter may be provided with suitable 35 graduations 42, numbered to assist the operator in identifying the proper holes for the insertion of the pin, as will be evident from an examination of Fig. 2. It should be understood, of course, that the spacing of the holes and of the graduations may be 40 made to suit the particular circumstances.

In the operation of the machine, the pin is inserted in the hole numbered 1, and the operator then proceeds to mark all of the 45 signatures of the first group. When the marking of these signatures has been completed, the operator then inserts the pin in the second hole, marks the second group, et cetera, until all of the signatures have been marked, after which the signatures are collated according to their marking, and if any 50 error should occur in assembling them, the fact will at once be made apparent by the irregularity in the arrangement of the marks, as they appear on the backs of the assembled signatures. By means of the 55 described machine and method, the marking of the signatures can be carried out accurately, expeditiously and economically.

Having thus described one embodiment of 60 the invention, but without limiting myself thereto, what I claim and desire by Letters Patent to secure is:

1. In a machine for marking book signatures, the combination of means for holding 65 a series of signatures in fixed position, a

signature marker, and means for moving said marker transversely of and in contact with said signatures.

2. In a machine for marking book signatures, the combination of means for holding 70 a series of signatures in fixed position, a signature marker, and means to cause rubbing engagement of said marker with said signatures while so held.

3. In a machine for marking book signatures, the combination of means for holding 75 a series of signatures in fixed position, an absorbent marker to which ink may be applied, and means for causing rubbing engagement of said marker with said signatures while so held, thereby to rub ink onto 80 said signatures.

4. In a machine for marking book signatures, the combination of means for holding 85 a series of signatures, and means for marking all of said signatures simultaneously.

5. In a machine for marking book signatures, the combination of a signature holder, 90 a signature marker, and means to bring said marker into contact with all of said signatures, simultaneously.

6. In a machine for marking book signatures, the combination of a signature holder, 95 a signature marker, and means to bring said marker into contact with all of said signatures, simultaneously, and to move said marker transversely of said signatures while in contact therewith.

7. In a machine for marking book signatures, the combination of a signature holder, 100 a signature marker, and means to utilize movement of said marker transversely of said signatures to cause movement of said marker into contact with said signatures.

8. In a machine for marking book signatures, the combination of a signature holder, 105 a signature marker, a marker carrier, and means to cause said carrier to move said marker first into contact with said signatures and subsequently transversely of said signatures while still in contact therewith.

9. In a machine for marking book signatures, the combination of a signature holder, 110 a signature marker, and means to cause a rubbing contact of said marker with all of said signatures simultaneously.

10. In a machine for marking book signatures, the combination of a signature holder, 115 a signature marker, means to guide said marker transversely of said signatures and means consequent upon movement of said marker transversely of said signatures to move said marker into contact with said signatures and subsequently to arrest the last-mentioned movement while permitting continuance of the first-mentioned movement.

11. In a machine for marking book signatures, the combination of a signature holder, 120 a signature marker, and a cam and follower 125

- to cause said marker to move into contact with said signatures and transversely thereof while in contact therewith.
12. In a machine for marking book signatures, the combination of a signature holder, a signature marker, a cam follower, and a marker carrier presenting a cam cooperating with said cam follower to move said marker into engagement with said signatures. 40
13. In a machine for marking book signatures, the combination of means for holding a series of signatures, a normally retracted signature marker, means for advancing said marker to carry the same into engagement with the signatures, and means of adjustment to vary the position of said marker lengthwise of said signatures. 50
14. In a machine for marking book signatures, the combination of means for holding a series of signatures, a signature marker, means for actuating said marker to carry the same into engagement with the signatures, and means of adjustment to vary the position of said marker and of its actuating means lengthwise of said signatures. 55
15. In a machine for marking book signatures, the combination of means for holding a series of signatures, a signature marker, marker actuating means, and means including a rack and pinion to adjust said marker and its actuating means lengthwise of said signatures. 60
16. In a machine for marking book signatures, the combination of means for holding a series of signatures, a normally retracted signature marker, marker advancing means, and means to adjust said marker and its advancing means lengthwise of said signatures. 65
17. In a machine for marking book signatures, the combination of means for holding a series of signatures, a signature marker, a carrier for said marker, means on said carrier for actuating said marker, a rack secured to said carrier, a pinion meshing with said rack, and means normally to hold said marker in the desired position of adjustment. 70
18. In a machine for marking book signatures, the combination of means for holding a series of signatures, a signature marker, a carrier for said marker, means for actuating said marker, means including a rack and pinion for adjusting said carrier and marker lengthwise of said signatures, and means of adjustment to hold said marker in the desired position. 75
19. The method of marking book signatures which is characterized by holding a series of signatures face to face, and marking all of said signatures simultaneously on their folded edges. 80
20. The method of marking book signatures which is characterized by holding a series of signatures face to face, and marking all of said signatures simultaneously by rubbing engagement therewith. 85
- In testimony whereof, I have signed my name to this specification.
- ROY C. BAKER.
